UNITED STATES PATENT OFFICE.

MARSHALL B. LLOYD, OF MENOMINEE, MICHIGAN, ASSIGNOR TO HEYWOOD-WAKEFIELD COMPANY, OF BOSTON, MASSACHUSETTS, A CORPORATION OF MASSACHUSETTS.

REED-BRAID-MAKING MACHINE.

Application filed May 14, 1924. Serial No. 713,201.

My invention relates generally to the manufacture of braid or edging for use in the reed article industry, but relates more particularly to the manufacture of a braid or edging of special form. When referring to reed, I mean to refer to the natural reed, fibre reed and other materials having these general characteristics and such materials as are used in the so-called reed industry.

10 In the manufacture of reed articles it is expedient at times and at other times, necessary, to use a braid or edging for finishing the article. Such braid should not only be ornamental so that it shall enhance the appearance of the article, but it should also be of such form that it will maintain its shape and be a factor in increasing the durability of the article as a whole. Such braid is employed at the corners, edges and other 20 very exposed places where it is likely to catch in the clothing of the user and where it is subjected to especially hard usage.

The general object of my invention is to provide a machine for the manufacture of a braid that shall be especially adapted for use in the reed article industry.

Another object of my invention is to provide a machine for making a reed braid, the machine being of such form and construction that materials available in the reed industry may be employed.

Again it is an object of my invention to provide a reed braid making machine that shall be automatic in operation, simple in construction, and durable in use, and whereby such braid can be produced rapidly and at low cost.

My invention consists generally in a machine of the form, arrangement, construction and cooperation of the parts, whereby the above named objects, together with others that will appear hereinafter, are attained; and my invention will be more readily understood by reference to the accompanying drawings which illustrate what I consider, at the present time, to be the preferred embodiment thereof.

In said drawings:

Fig. 1 is a perspective view of a machine embodying my invention.

Fig. 2 is a detail view of the stake guiding rolls.

Fig. 3 is a vertical sectional view substantially along the line 3—3 of Fig. 4.

Fig. 4 is a top plan view.

Fig. 5 is a horizontal sectional view, substantially along the line 5—5 of Fig. 3.

Fig. 6 is a transverse vertical sectional view substantially along the line 6—6 of Fig. 3.

Fig. 7 is a detail horizontal sectional view of the stake guiding blocks.

Fig. 8 is a detail view, partly in elevation and partly in section, of the strand inserting device.

Fig. 9 is a detail sectional view, substantially along the line 9—9 of Fig. 8; and

Figs. 10, 11 and 12 are descriptive views illustrating the intertwining of the stakes and strands.

The machine, as here shown, comprises a pair of suitably braced legs 1 upon which there is supported a table plate 2 of appropriate size and shape. The table is provided with a transverse slot 3, which is bordered by the ledges 4 and 5 and which, together with the overhanging strips 6 and 7 form a guideway for the slidable table 8. On the bottom of the table 8 is a gear rack 8^a which meshes with the certain gear pinions later to be described and whereby reciprocating movement, at proper timed intervals, is imparted to the table 8.

Mounted upon the slidable table 8, in this instance, are two reels 9 and 10, being carried in the standards 11 on the shaft 12. These reels are rotatable on the shaft 12 so that the strands 13 and 14, respectively, may be withdrawn as will appear shortly. The strands 13 and 14, in this instance, are of the same material as is used for filler strands of reed or fibre reed articles, i. e. they are rather flexible, as distinguished from the relatively stiff character of the stake material with which they are intertwined in a manner shortly to be described. These characteristics, however, are to be considered purely as illustrations and not as limitations, except only as may be necessary by limitations in the claims.

At the top of the standards 11 are two bars 15 and 16, respectively, which are spaced apart to provide a guideway for the slidable block 17. Mounted in the slidable

block 17 so that it may swivel therein is a member 18, the upper end 19 of which is in the shape of a curved finger. The member 18 is hollow and receives the two strands 13 and 14 and the finger portion 19 is hollow and flattened so that the strands 13 and 14 are caused to emerge in intimate side by side relation, one over the other. In order to maintain the strands 13 and 14 under proper tension I provide tension device composed of the fixed member 20 and the movable block 21, between which the strands 13 and 14 pass.

By means of the screw 22 which is tapped into the member 20 and the compression spring 23, the magnitude of the pressure upon the strands can be varied to place them under the desired tension.

The strands 13 and 14 are intertwined, in the present instance, with two sets of what I shall term, stakes, each set being composed of three stakes arranged in side by side relation. The arrangement of the stakes is probably best shown in Figs. 10, 11 and 12, wherein the stakes of one set or group have been given the reference characters 24^a, 24^b and 24^c and those of the other group 25^a, 25^b and 25^c. The reason I refer to these as stakes is that I prefer to utilize elements which are quite rigid relative to the flexibility of the strands 13 and 14, elements similar to the stakes of a stake and strand reed fabric or fibre reed fabric being satisfactory. In the present instance, the stakes shown are provided with metallic cores 26 and 27, which serve to give additional stability to the finished braid.

Before describing the remainder of the machine in detail, it will be helpful to describe the intertwining of the strands with the stakes, which operation will be best understood by reference to the descriptive views 10, 11 and 12. The stakes 24^a, 24^b and 24^c pass through an opening 28 in the upper part 29 of what I shall term a stake shifting and strand packing arm 30. The slot or opening 28 is elongated in form and of a width just sufficient to accommodate the stakes so that the stakes, in passing therethrough, are arranged in contacting relation and are positioned in a single plane. The stakes 25^a, 25^b and 25^c pass through the opening 31 in the upper portion 32 of a similar stake shifting and strand packing arm 33, the arrangement of the arms 30 and 33 being such that the two nearest stakes 24^a and 25^a are spaced a slight distance apart. Now, assuming the arms 30 and 33 to be swung in opposite directions so that they are disposed at an angle to what may be termed the neutral vertical plane, and the parts to be in the position shown in Fig. 10, the table carrying the reels 9 and 10 will be shifted to the right, i. e. in the direction of the arrow 34, in Fig. 10. As the table 8

moves in that direction it will cause the swivel member 18 carrying the finger portion 19 to swing so that the finger 19 points in the opposite direction, i. e. in the direction shown in Fig. 11. As the table 8, 70 standards 11 and the parts carried thereby continue their movement in the direction of the arrow 34 the two strands 13 and 14 are caused to pass between the two groups of stakes so that when the finger 19 reaches 75 the limit of its movement in the direction of the arrow 34, as shown in Fig. 12, and as the stake shifting and filler strand packing arms 30 and 33 have been brought to the normal vertical plane it will be found that 80 these strands 13 and 14 will have passed over one group of stakes and onto the other or, since these terms are relative, it may be said that the strands have passed upon one side of one group of stakes and upon the 85 other side of the other group. Now, the next movement is to swing the arm 33 in the direction of the arrow 35 and to swing the arm 30 in the direction of the arrow 36 (see Fig. 12), these arms swinging until a condition is reached similar to the condition of the arms 30 and 33, except that they will then occupy positions upon opposite sides of the central plane from the positions which these arms occupy in Fig. 10. When such 95 position has been reached mechanism is set in motion which causes the table 8 to reverse its movement so that the swivel member 18, and the finger 19 carried thereby is moved in the direction of the arrow 37 (see Fig. 100 12) whereupon it will be obvious that the strands 13 and 14 will be caused to pass upon opposite sides of the groups of stakes 24^a, 24^b, 24^c and 25^a, 25^b and 25^c. In this 105 manner, by the continued shifting of the arms 30 and 33 and the back and forth movement of the strand inserting finger 19 a braid construction similar to that shown in Fig. 12 is formed. In this connection I might add that in Fig. 12 the two groups 110 of stakes have been shown spaced a greater distance apart than would normally be the case, this being done simply to make the illustration somewhat clearer.

The arms 30 and 33 not only serve to shift 115 or swing the stakes from the normal plane but they also serve to pack the strands 13 and 14 of the respective courses tightly, one course against the other. This is accomplished by so arranging the relative positions of the parts that as the arms 30 and 33 come to the neutral plane, i. e. as they reach a central vertical position, the upper ends 30^a and 33^a press upwardly against strands 13 and 14 (see Fig. 12). This action will be furthermore apparent by reference to Fig. 3 which shows the arms 120 disposed at a considerable angle to the central neutral plane and clearly indicates that when these arms are moved to the central 125 130

plane they must likewise have an upward motion. This particular function of the arms 30 and 33 will be referred to as packing the strands.

5 It will be understood that the arms 30 and 33 are held in spreading relation a sufficient length of time to permit the passage of the reels 9 and 10, the standards 11 and the parts carried thereby therethrough.

10 The stake shifting and strand packing arms 30 and 33 are pivotally secured to members 40 and 41 at 42 and 43, respectively. The members 40 and 41 are secured rigidly to blocks 44 and 45, respectively.

15 The block 44 is slidably mounted upon spaced rods 46 and 47 and the block 45 upon similarly spaced rods 48 and 49. The blocks 44 and 45 are connected together by an endless cable 50 which passes around the

20 spaced pulleys 51 and 52 which, in turn, are mounted upon the vertical shafts 53 and 54. The upper ends 55 and 56 of the members 40 and 41 are enlarged and engage rollers 57 and 58 whereby these members are guided

25 at their upper ends.

From this description it should be obvious that if the endless cable 50 is moved it will cause movement of both of the members 40 and 41, but in opposite directions. I, therefore, provide means for moving the cable 50 a predetermined distance in one direction, means for causing it to remain at rest while the strand reels are moved through the angularly disposed stake shifting and 35 strand packing arms, and means for reversing the movement of the cable 50 to shift the arms 30 and 33, as before described, in connection with the descriptive figures 10, 11 and 12.

40 *The driving mechanism.*

Mounted upon the main drive shaft 60 is a loose pulley 61 and a fixed pulley 62, the belt 63 being shiftable from one to the other 45 by the belt shifter 64.

At the end opposite to the drive pulley there is secured to the shaft 60 a pinion gear 65 which meshes with a large gear 66 that is mounted upon the shaft 67. Also 50 mounted upon the shaft 67 is a bevel gear 68 which meshes with a bevel gear 69 that is carried by the short shaft 70. The shaft 70 is carried in spaced bearings 71 and 72 and therebetween and secured to rotate with 55 the shaft 70 is a wheel 73 of special construction and which is best shown in Fig. 3. Thus, the wheel 73 is provided with diametrically opposed gear segments 74 and 75 between which there extend smooth faced 60 segments 76 and 77.

65 Mounted parallel to the shaft 70 is a shaft 78 on which is fixed a wheel 79 which, in turn, is provided with gear segments 80 and 81 and smooth segments 82 and 83. In this manner, the shaft 70 is constantly driven

and the shaft 78 is driven when the gear segments of the wheels 73 and 79 are in mesh and is idle when the smooth segments of these wheels contact, one with the other.

70 Mounted upon the shaft 78 is an arm 84 in such position that when the shaft 78 comes to rest in one position it will be in the position shown by full lines in Fig. 3 and when the shaft 78 comes to rest after a half revolution it will be in the dotted line position 75 shown in Fig. 3. By means of a link 85, the arm 84 is connected to the slideable block 45. In this way, movement is imparted to the endless cable 50 causing driving and reverse movement thereof with the result before described.

75 For operating the reel shifting table, I provide a gear 86 which is carried by a suitably mounted shaft 87. The gear 86 is given an oscillating movement from the gear 66 by means of the arm 88, one end of which is pivotally connected to a stud 89 carried by the gear 66 and the other end of which is pivotally connected to a stud 90 carried by the gear 86.

80 Mounted in suitable bearing carried by the table of the machine will be found parallel shafts 91 and 92 which, at their outer ends, carry gears 93 and 93, respectively, and at their inner ends, gears 95 and 96. 95 Since either one of gears 95 or 96 is always in mesh with the gear rack 8^a on the bottom of the reel carrying table 8 it is obvious that not only is the table 8 shifted back and forth but that it moves to just the right extent and at just the proper time, considering the movement of the stake shifting arms 30 and 33, since they are all driven from a common source.

90 *General features.*

105 The stake material is mounted upon suitable reels (not shown) and passes through eyes 100 and 101, thence to a centrally located eye 102 to eyes carried by the stake shifting and strand packing arms 30 and 33 and finally to the tip portions 29 and 32.

110 The finished braid passes between the guide blocks 103 and 104, thence between the soft rubber rolls 105 and 106 and on to the reel 107. Roll 106 is mounted upon a shaft 108 which is periodically advanced by means of the ratchet wheel 109 carried thereby and the pawl 110 carried by the swingable arm 111. Arm 111 is swung back 115 and forth by means of the vertical roll 112 which is slidably mounted in bearings 113 and 114, and the lower end of which carries a roller 115 which is engaged by the cam block 116 mounted upon the face of the wheel 86. The upper end of the rod 112 is connected to an arm 117 that is mounted upon the shaft 118, which shaft also carried an arm 119, the arm 119 being connected to the pawl carrying arm 111 by 120 125 130

the link 120. The rod 112 is depressed, by the compression spring 121. In this manner periodic movement is imparted to the rolls 105 and 106, since the shafts on which these rolls are mounted carry the gears 105^a and 106^a which are in mesh (see Fig. 1).

In order to facilitate inspection the roll 105 and the guide block 103 are arranged to be moved away from the roll 106 and the guide block 104. To this end the part carrying the block 103 and the roll 105 is mounted for sliding movement in a slot or guideway 122 in the plate 123 on which the various parts are mounted. The plate 123 is suitably supported from the table of the machine by means of the standards 124. Also mounted on the plate 123 is a fixed block 125 in which is carried a shaft 126. At one end of the shaft 126 is a hand lever 127 and at the other end an arm 128, which by means of a link 129 is connected to the stud 130 of the frame that carries the block 103 and roll 105. By swinging the hand lever 127 in a clockwise direction (viewed as in Figs. 1 and 2) the roll 105 may be retracted and by swinging in reverse direction the parts are restored to their operative positions.

The reel 107 is rotated by means of the belt 131 which operates over the pulley 132 that is mounted upon the shaft 108 and the pulley 133 that is carried by the reel shaft 134.

As the finished braid leaves the braiding mechanism on its way to the reel 107 it is suitably guided by the guide member 135 leaving the same along the general direction of the dotted lines 136 (Fig. 3) the exact angle being dependent upon the amount of braid upon the reel 107.

In the claims I shall use the term stakes merely to distinguish them from the strands which are intertwined therewith so that the term stakes should not be held to be a limitation but simply an illustration of a suitable material and to avoid confusion of terms.

The machine is automatic in operation, durable in construction and produces a braid product which is exceptionally well adapted for use in the reed article industry.

I claim:—

1. A reed braid making machine embodying therein means for shifting a plurality of aligned but spaced stakes to opposite sides of a neutral plane, and means for winding a strand in enveloping relation so that it passes back and forth and over and under the stakes, said stake shifting means operating to pack the strand in place.

2. A reed braid making machine embodying therein means for shifting a plurality of aligned but spaced stakes to opposite sides of a neutral plane, and means for winding a strand in enveloping relation so that it

passes back and forth and over and under the stakes, said strand winding device including a swivelled strand guiding device, and said stake shifting means operating to pack the strand in place.

3. A reed braid making machine embodying therein means for shifting a plurality of aligned but spaced stakes to opposite sides of a neutral plane, and means for winding a strand in enveloping relation so that it passes back and forth and over and under the stakes, said strand winding device including a swivelled strand guiding device, and means for causing reciprocatory movement of the strand guiding device, said stake shifting means operating to pack the strand in place.

4. In a reed braid making machine, the combination of means for shifting a plurality of stakes with means for intertwining a strand therewith, said stake shifting means including means for holding the stakes at an angle to the neutral plane whilst the strand is passed over one stake and under the other, said stake shifting means acting in its movement to pack the previously intertwined strand.

5. In a reed braid making machine, the combination of means for shifting a plurality of stakes with means for intertwining a strand therewith, said strand intertwining means including a strand carrying reel, a strand guiding finger, and means for reciprocating them, said strand guiding finger being mounted for sliding movement relative to the reel.

6. In a reed braid making machine, the combination of means for shifting a plurality of stakes with means for intertwining a strand therewith, said strand intertwining means including a strand carrying reel, a swivelled strand guiding finger and means for reciprocating them, said strand guiding finger being mounted for sliding movement relative to the reel.

7. In a reed braid making machine, the combination of means for shifting a plurality of stakes with means for intertwining a strand therewith, said strand intertwining means including a strand carrying reel and a strand guiding finger, means for imparting a reciprocating movement to said reel and finger, said finger being mounted for a sliding movement, relative to said reel, and a tension means movable with the finger for imposing a tension on said strand.

8. In a reed braid making machine, the combination of means for shifting a plurality of stakes with means for intertwining a strand therewith, said strand intertwining means including a strand carrying reel and a swivelled strand guiding finger, means for imparting a reciprocating movement to said reel and finger which finger is mounted for a sliding movement with respect to the

reel, and a tension device movable and swivelling with the finger for imposing a tension on said strand.

9. In a reed braid making machine, the combination of means for shifting a plurality of stakes with means for intertwining a strand therewith, said stake shifting means including two arms, slidable members to which the lower ends of said arms are pivotally secured, and means for moving said slidable members.

10. In a reed braid making machine, the combination of means for shifting a plurality of stakes with means for intertwining a strand therewith, said stake shifting means including two arms, slidable members to which the lower ends of said arms are pivotally secured, and means for moving said slidable members in opposite directions.

11. In a reed braid making machine, the combination of means for shifting a plurality of stakes with means for intertwining a strand therewith, said stake shifting means including two arms, slidable members to which the lower ends of said arms are pivotally secured, and means for moving said slidable members in opposite directions, and for holding them in a state of rest for a predetermined period at the end of the path of movement of the slidable members.

12. In a reed braid making machine, the combination of means for shifting a plurality of stakes with means for intertwining a strand therewith, said stake shifting means including two arms, slidable members to which the lower ends of said arms are pivotally secured, and means for moving said slidable members in opposite directions, and for periodically reversing the direction of movement of said slidable members.

13. In a reed braid making machine, the combination of means for shifting a plurality of aligned but spaced stakes to opposite sides of a neutral plane, with means for winding a strand in enveloping relation so that it passes back and forth and over and under the stakes, said strand winding means including a reel, a slidable table on which the reel is mounted, and means for causing reciprocatory movement of the table.

14. In a reed braid making machine, the combination of means for shifting a plurality of aligned but spaced stakes to opposite sides of a neutral plane, with means for winding a strand in enveloping relation so that it passes back and forth and over and under the stakes, said strand winding means including a reel, a slidable table on which the reel is mounted, and means for causing reciprocatory movement of the table, said table reciprocating means including a gear rack and pinion.

15. In a reed braid making machine, the combination of means for shifting a plurality of aligned but spaced stakes to opposite

sides of a neutral plane, with means for winding a strand in enveloping relation so that it passes back and forth and over and under the stakes, said strand winding means including a reel, a slidable table on which the reel is mounted, and means for causing reciprocatory movement of the table, said table reciprocating means including a gear rack and a plurality of spaced pinions, at least one of which is always in engagement with the table.

16. In a reed braid making machine, the combination of means for shifting a plurality of aligned but spaced stakes to opposite sides of a neutral plane, with means for winding a strand in enveloping relation so that it passes back and forth and over and under the stakes, said strand winding means including a reel, a slidable table on which the reel is mounted, and means for causing reciprocatory movement of the table, said table reciprocating means including a gear rack and a plurality of spaced pinions, at least one of which is always in engagement with the table, together with means for driving and reversing said pinions.

17. A reed braid making machine embodying therein, stake shifting means including arms, each operatively engaged at one end with spaced stakes, and means for moving the other ends of said arms in opposite directions from one side to the other of a neutral plane, said arms swinging about a shifting fulcrum provided by an endwise movement of the first mentioned ends of said arms on said stakes, and means for interweaving a continuous strand over and under said stakes.

18. A reed braid making machine embodying therein, stake shifting means including a pair of arms each engaged at one end with spaced stakes, and means for imparting a swinging movement to the other ends of said arms about a fulcrum shiftable longitudinally of the stakes so that said arms swing from one side to the other of a neutral plane and means for interweaving a continuous strand upon said stakes.

19. A reed braid making machine embodying therein, stake shifting means including a pair of arms each engaged at one end with spaced stakes, and means for imparting a swinging movement to the other ends of said arms about a fulcrum shiftable longitudinally of the stakes so that said arms swing from one side to the other of a neutral plane and means for interweaving a continuous strand upon said stakes, said first mentioned ends of said arms acting to pack the interwoven strand upon said stakes.

20. A reed braid making machine embodying therein, stake shifting means including a pair of arms, each having an opening at one end for the passage therethrough of spaced stakes, and means for

- 6
imparting a movement to the other ends of said arms about a shifting fulcrum on said stakes provided by a longitudinal movement of the first mentioned ends of said arms thereon so that said arms swing from one side to the other of a neutral plane, and means for interweaving a continuous strand upon said stakes. 21. A reed braid making machine embodying therein, braid guiding means, stake shifting means including a pair of arms each engaged at one end with spaced stakes at a point adjacent the braid guide, means for imparting a swinging movement to said arms in opposite directions about a fulcrum shiftable on said stakes toward and away from the braid guide and means for interweaving a strand upon said stakes. 22. A reed braid making machine embodying therein, braid guiding means, stake shifting means including a pair of arms each engaged at one end with spaced stakes at a point adjacent the braid guide, means for imparting a swinging movement to said arms in opposite directions about a fulcrum shiftable on said stakes toward and away from the braid guide and means for interweaving a strand upon said stakes, said ends of said arms providing said shifting fulcrum acting in the movement thereof toward said braid guide to pack the strand upon said stakes. 23. A reed braid making machine embodying therein, braid guiding means, stake shifting means including a pair of arms engaged at one end with spaced stakes at a point adjacent the braid guide, means for imparting a swinging movement to said arms in opposite directions about a fulcrum shiftable on said stakes toward and away from the braid guide, a reciprocating strand reel supporting carriage movable transversely across the path of movement of said swinging arms and a finger carried thereby for interweaving a portion of said strand upon said stakes. 24. A reed braid making machine embodying therein, braid guiding means, stake shifting means including a pair of arms engaged at one end with spaced stakes at a point adjacent the braid guide, means for imparting a swinging movement to said arms in opposite directions about a fulcrum shiftable on said stakes toward and away from the braid guide, a reciprocating strand reel supporting carriage movable transversely across the path of movement of said swinging arms, a swivelling finger, shiftable on the carriage in the direction of its movement for interweaving a portion of said strand upon said stakes. 25. A reed braid making machine embodying therein, braid guiding means, stake shifting means including a pair of arms engaged at one end with spaced stakes at a point adjacent the braid guide, means for imparting a swinging movement to said arms in opposite directions about a fulcrum shiftable on said stakes toward and away from the braid guide, a reciprocating strand reel supporting carriage movable transversely across the path of movement of said swinging arms, a swivelling finger, shiftable on the carriage in the direction of its movement for interweaving a portion of said strand upon said stakes, said ends of said arms providing said shifting fulcrum acting in the movement thereof toward said braid guide to pack the strand upon said stakes. 26. A reed braid making machine embodying therein, a table, a strand reel carriage reciprocable in one direction thereon, a braid guide positioned above the table in the plane of movement of said carriage, a pair of arms each slidably engaged at one end with spaced stakes at a point near said braid guide, and capable of a swinging movement in opposite directions and transversely of the plane of movement of said carriage. 27. A reed braid making machine embodying therein, a table, a strand reel carriage reciprocable in one direction thereon, a braid guide positioned above the table in the plane of movement of said carriage, a pair of upright plate members, reciprocable on the table in opposite directions in a plane transversely of the plane of movement of the carriage, an arm pivoted at its bottom end to each upright member and having a part at its top end engaged with and supported by spaced stakes, and a finger on said carriage for laying the strand upon said stakes. 28. A stake shifting mechanism for a reed braid making machine embodying therein two arms each having a part at one end through which spaced stakes may pass in a predetermined plane, the other ends of said arms moving in opposite directions from one side to the other of said plane, in which plane the first mentioned ends of said arms are reciprocable. In testimony whereof, I have hereunto set my hand, this 10th day of May, 1924.

MARSHALL B. LLOYD.
